UNITED STATES PATENT OFFICE.

MORRILL A. SHEPARD, OF LEBANON, ILLINOIS.

COMBINED CHAIN AND ELEVATOR-BUCKET.

SPECIFICATION forming part of Letters Patent No. 300,518, dated June 17, 1884.

Application filed December 1, 1883. (No model.)

To all whom it may concern:

Be it known that I, MORRILL A. SHEPARD, of the city of Lebanon, in the county of St. Clair and State of Illinois, have invented a new and Improved Combined Chain and Elevator-Bucket, which improvement is fully set forth in the following specification, reference being had to the accompanying drawings, in which—

10. Figure 1 is a top view. Fig. 2 is a side elevation. Fig. 3 is an end elevation.

The object of this combined chain and bucket is to obtain a chain that can be made in sections, so as to be readily put together or taken 15 apart without any bolts, rivets, or open links, and in putting the sections of the chain together the elevator-bucket is securely clasped between two of the links or sections that make up a part of the chain, thereby dispensing 20 with the ordinary rivets or bolts usually employed to secure the elevator-bucket to the belt or chain.

The bucket consists of a cup, *a*, clamped in a basket consisting of two metal frames, *b*. Each frame spreads into two bars, *c*, to embrace the cup, and then the frame ends in ears 25 *d* at bottom and top, through which pass the heads *e'* of the I-formed coupling-link *e*. At

the side of the hole in the ear *d* is a notch, through which passes a stud, *e''*, of the link-head *e'*; when the end of the head is being inserted, then the link is turned to its proper position in line with ear *d*. The stud *e''* prevents the ear from being pulled off the end of the head. The bucket has central supports 35 on the chain, and in the event of wear of the bucket on these supports it can be turned in the cage-frame from the point of wear.

The whole chain consists of three pieces of suitable metal, (preferably malleable or wrought iron,) two out of the three being duplicates. So a whole elevator-chain would consist of a number of duplicate pieces of two kinds—namely, half-cages and coupling-pieces.

45. I claim as my invention—

1. An elevator-bucket secured between two sections of the elevator-chain, substantially as described and set forth.
2. The elevator-chain composed of sections, substantially as described.

MORRILL A. SHEPARD.
